[57] CLAIM

The ornamental design of a ski carrier, as shown and described.

DESCRIPTION

FIG. 1 is a perspective view of a ski carrier showing our new design;

FIG. 2 is a reduced scale perspective view of the ski carrier in an operative condition;

FIG. 3 is a top plan view of FIG. 1 in an extended condition; and

FIG. 4 is a side elevational view of FIG. 1 in an extended condition.
